UNITED STATES PATENT OFFICE.

JOHN E. WADE, OF NEW YORK, N. Y.

CAR-COUPING.

No. 816,951.

Specification of Letters Patent.

Patented April 3, 1906.

Application filed December 14, 1904. Serial No. 236,798.

To all whom it may concern:

Be it known that I, JOHN E. WADE, a citizen of the United States, residing in the borough of Brooklyn, in the city of New York, county of Kings, and State of New York, have invented certain new and useful Improvements in Car-Couplings, of which the following is a specification, reference being had therein to the accompanying drawings, which form a part thereof.

My invention relates to car-couplings, and more particularly to a class of couplings having a laterally-movable locking-jaw.

The main object of the invention is to provide a coupling of this character which while possessing a sliding self-actuating locking-jaw will be capable of coöperating with all couplings now commonly used employing the ordinary Janney type of swinging locking-jaws.

20 A further object is to provide such a coupling which upon the operative impact of an opposed coupling therewith will be automatically opened to receive such and instantly upon the passage of the locking-jaw 25 of the opposed coupling resume its normally locked position through gravity.

A still further object is to provide a coupling of this character having guides and stays so arranged as to permit the movement of 30 said locking-jaw and yet under all conditions impart that strength and durability to the coupling necessary to meet the great strains thereon when in use.

35 A still further object is to so arrange these guides and stays as to distribute said strains in a manner to prevent the release of the interlocked jaws thereby.

40 A still further object is to provide a coupling the head of which will be so constructed as to give the necessary clearance for the movement of the sliding jaw of an opposed coupling.

45 A still further object is to provide in such a coupling for the proper play to permit the taking of curves and at the same time means whereby movement resulting from such play will be so limited as to avoid the release of the locking-jaws thereby.

50 A still further object is to provide means limiting the extent of movement of the locking-jaw to avoid displacement thereof through excessive force in bringing opposed couplings together.

55 A still further object is to provide for the locking of opposed couplings when there is a

difference in the relative height thereof; and a still further object is to provide a coupling which comprises a minimum of moving parts, which will be strong and not susceptible of breakage through the ordinary exigencies of use, and which cannot become readily disarranged.

The invention consists, primarily, in providing a car-coupling comprising a draw-bar, a draw-head, a laterally-pitched inclined seat or way on one horn thereof, an oppositely-disposed side horn, a non-rotary slideable locking-jaw having a contour like that of the Janney type of coupling mounted and having direct movement on said seat or way, and means carried by said jaw whereby the drawing strains thereon are transmitted to said draw-head and said draw-bar, and in such other novel features of construction and arrangements of parts as are hereinafter set forth and described, and more particularly pointed out in the claims hereto appended.

Referring to the drawings, Figure 1 is a perspective view of a coupling embodying my invention, showing the locking-jaw in the position assumed upon the impact of an opposed coupling. Fig. 2 is a plan view of said coupling with the parts in their normal position. Fig. 3 is a section on the line 3 3 of Fig. 2. Fig. 4 is a side elevation of the coupling, and Fig. 5 is a perspective view of the draw-head and draw-bar with the locking-jaw entirely removed.

Like letters refer to like parts throughout the several views.

In the drawings the draw-bar is shown as of ordinary construction, comprising parallel bars *a a'*, suitably braced and so arranged as to provide a space for the draft-rigging. (Not shown.) The forward ends of these bars are extended laterally to form the draw-head *b*, having the side horn *b'* with its outer curved guide-face, carrying the locking-jaw and the oppositely-disposed side horn *b''*, the space within said draw-head and said horns being similar in contour to that of the ordinary Janney type of coupling and having the usual curved surfaces for guiding the opposed couplings to the locked position. The side horn *b'* is projected across the open portion of the draw-head to a greater extent than in the ordinary Master Car-Builders' coupling to form a horizontal ledge or rest *c* thereon, and from this ledge or rest the said horn slopes upwardly at an angle approximating forty-

five degrees to form an inclined seat c' , the outer wall of which is curved to conform to the lower portion of said side horn.

The upper bar a is cut away above this inclined seat c' and ledge or rest c , leaving the spur d , which serves in part as a guide and stop for the laterally-slidable jaw e and a buffer for the locking-jaw of an opposed coupling, as will more fully appear hereinafter, and to 10 form a guide slot or way d' in said bar to aid in controlling the movement of said jaw and taking up the drawing strains thereon. The under side of the guide slot or way is preferably undercut at an angle corresponding with 15 that of the inclined seat c' , thus forming an opposed bearing parallel therewith.

The lower bar a' has extending therethrough an inclined guide slot or way d^2 , having the same pitch as the way d' and having 20 the same functions. It will be observed that the ways $d' d^2$ are disposed on opposite sides of the center line of the draw-bar, thus insuring the application of the drawing strains at a point intermediate between said bearings or along substantially the center line of 25 said bar, thus avoiding, as will more fully appear hereinafter, a tendency of such strains to release the locking-jaws.

The side horn b^2 is provided on the lower 30 bar a' only, the space above said horn being required to be clear to permit the upward outward movement of the sliding jaw e of an opposed coupling. To compensate for that variance in the heights of opposed couplings, 35 I extend this horn both above and below said bar for several inches, which does not interfere with the movement of such jaw, yet insures the engagement of this horn with an opposed coupling in locking, even if it be 40 either higher or lower. This also imparts additional strength to this part.

If desired, a rabbet may be provided in the seat c' , adapted to coöperate with a fillet or bead on the jaw e to aid in guiding said jaw 45 and in transmitting draft strains therefrom to the draw-bar.

The locking-jaw e as to its buffer and locking faces is substantially like that of the ordinary Master Car-Builders' coupling. In- 50 stead of being secured to the draw-head by means of trunnions, however, it is non-rotary, being provided with a lower inclined face e' , adapted to move on the seat c' , with horizontal lower faces e^2 , adapted to engage and 55 rest upon the ledge or rest c , and when I employ the spur d with an upper face parallel with said seat e^3 and a stop-shoulder e^4 . As stated, I may, if desired, provide a fillet or bead e^5 thereon to coöperate with the rabbet 60 c^2 on said seat. This jaw is extended rear- 65 wardly of the head b and is provided with a top flange f , an inclined flange f' , adapted to enter the way d' , and an extension f^2 thereof, operating in the way d^2 . The pitch of in- clination of said flange and said extension is

the same as that of the inclined seat c' and the said ways $d' d^2$.

To facilitate the use of this coupling with an ordinary coupling-link, I provide the usual cut g therein and the openings therein for the 70 coupling-pin.

The stops f^3 , carried by the extension f^2 , are adapted to contact with the bar a' and prevent the jaw e being forced entirely from the draw-head.

In practice a coupling is not only subject to extremely rough usage, but to such movement relative to an opposed coupling, vibrations, and play in making curves as to make it advisable to provide means limiting such 80 to an extent to prevent one laterally-slidable jaw being gradually worked backward by another when the latter is higher than it. To this end I provide several safeguards, as a slight bulge within the jaws at h , adapted to 85 engage the forward face of the ledge or rest c , an overhung incline i on the spur d , adapted to equalize to a limited extent the height of opposed couplings, and a stop j on the lower 90 forward face of the ledge or rest c , but to one side thereof, adapted to engage with a stop on the under side of an opposed coupling similar to that, j' , shown. The tendency of any 95 of these is to interpose a positive limitation to such relative movement of opposed couplings as would crowd back the jaw e to a point sufficient to permit the locking-jaw of an opposed coupling to escape therefrom. The 100 jaw e is provided with an eye k or other means whereby it may be manually operated to release opposed couplings.

The herein-described coupling, it will be observed, is adapted to receive and couple with any coupling of the Master Car-Builders' type or employing the Janney type of 105 locking-jaw, inasmuch as my coupling when locked is substantially identical with such types as to the contour and disposition of the operative parts, except as to the limitations as to the height of the side horn b^2 . If upon 110 the impact of either of said types therewith its locking-jaw be closed, the contact of said jaw with the jaw e will cause said latter jaw to open sufficiently to permit the said other jaw to pass, provided the pitch of the seat c' be increased so as to avoid a wedging of said 115 jaw e and the ordinary side horn and the buffer-face of said jaw e be made full toward the bottom thereof to insure the proper application of the force of the impact, while if said other jaw be open it will pass between the jaw e and the side horn b^2 and be forced into place behind said jaw e without opening said jaw. The outer end of said coupling, both 120 within and without said draw-head, said 125 horns, and said locking-jaw presents generally the same arrangement of curved contacting surfaces and engaging surfaces found in these other types now in general use.

It being apparent that one coupling is op- 130

erative in this connection and to the extent above referred to in the same manner as with a twin coupling, a description of its mode of operation in the latter connection only will 5 be entered into.

As twin couplings embodying my invention contact, if they be perfectly alined, the jaws being normally in the closed position, the outer faces of the opposed locking-jaws *e* en-

10 gage upon their rounded surfaces and the impact forces one or both of them off the ledge or rest *c*, upon which it normally rests, up the incline *c'* until the lateral movement is sufficient to permit the passage of the opposed 15 coupling's locking-jaw. If the couplings be not so alined, the contact of the outer curved side of the horn *b'* and the side horn *b''* will force them to position, the said side horn *b'* once within the jaws of the coupling being 20 acted on by the curved surfaces within said head to under all conditions force opposed 25 couplings into the proper position.

The arrangement of the guides or ways *d'* *d''* the flange *f'* and the extension *f''*, the normal projection of the locking-jaw *e* to a point substantially on and beyond the center line 30 of the draw-bar and when used the bead *e⁵* and rabbet *c²* avoid such a twisting movement of said jaw and binding of the various parts 35 as would tend to interfere with the free start and subsequent movement of said jaw.

When the jaws *e* of opposed couplings have passed one beyond the other, gravity instantly restores each of said jaws to its former position, thus automatically locking the 40 coupling.

The strain upon the coupling in use to prevent the accidental release thereof must be confined to substantially along the center 45 line of the draw-bar, as excessive side movement thereof would tend to gradually work up one jaw to a point where the other jaw could escape therefrom. The contact of the rest *c* with the bulged portion at *h* will tend 50 to avoid lateral play of the couplings beyond that necessary to take curves, as will also that of the stop *j* with the contact *j'* of an opposed coupling when the opposed couplings are at different heights. It may be observed 55 at this point that the arrangement of the stop *j* to one side of the center line of the draw-bar and below the bar *a* will cause this stop to be inoperative as to the wall within the said jaws. The spur *d* being in contact with 60 an opposed jaw *e*, toward the top thereof, will tend to check movement thereof and also exert a pressure on said jaw, which will tend to hold it upon its seat *c'*, the overhung incline *i* aiding in this action.

65 The top flange *f*, inclined flange *f''*, and extension *f''* serve to take up and so distribute the strains on the jaw *e* as to give to the draw-head and draw-bar a substantially straight pull, as well as to guide the movement of said jaw *e* by reason of the opposed bearings af-

ficed by the guides *d'* *d''*, parallel with the seat *c'*. The fillet *e⁵* and rabbet *c²* aid in this result when used.

While the spur *d* must be of sufficient strength to avoid likelihood of breakage from 70 heavy objects falling thereon, it will be observed that the jaw *e* being normally closed, will give a backing thereto, which tends to avoid this danger.

To release the coupling, it is merely necessary to manually draw one of the jaws *e* along the incline *c'* by means of the eye *k* or other means for this purpose provided.

A coupling as herein described comprises 80 but one movable part, and through the distribution of the strains, as described, the wear is so distributed as to prevent the coupling giving out at any one point. It is always prepared for coupling, and its action, except upon uncoupling, is entirely automatic, thus not requiring the presence of a brakeman or train hand to adjust same preparatory to bringing the cars together. It is simple in design and construction and is oper- 85 ately with all those couplings now generally in use of the types referred to.

While I have described the preferred pitch of the incline *c'* as being forty-five degrees, it is apparent that this pitch may be varied as desired.

It is not my intention to limit the invention to the precise details of construction as herein shown and described, as such may be varied without departing from the spirit and scope of the invention.

Having described the invention, what I claim as new, and desire to have protected by Letters Patent, is—

1. A car-coupling comprising a draw-bar, a draw-head, an inclined seat thereon, an oppositely-disposed side horn, a non-rotary slid- 105 able locking-jaw having a contour like that of the Janney type of coupling mounted and having direct movement on said seat or way, and means carried by said jaw whereby 110 the drawing strains are transmitted to said draw-head and said draw-bar.

2. A car-coupling comprising a draw-bar, a draw-head comprising a side horn on the lower portion thereof, an inclined seat or way 115 thereon, an oppositely-disposed lower side horn, an upper guide or buffer within said horns, a lower guide or buffer connecting said horns, a non-rotary slid-able locking-jaw having a contour like that of the Janney type of 120 coupling mounted and having direct movement on said seat or way, and means carried by said jaw whereby the drawing strains are transmitted to said draw-head and said draw-bar.

3. A car-coupling comprising a draw-bar, a draw-head comprising a side horn on the lower portion thereof, an inclined seat or way 125 thereon, an oppositely-disposed lower side horn, an upper guide or buffer within said 130

4

horns, a lower guide or buffer connecting said horns, guides or ways in said draw-head rearwardly of said guides or buffers and disposed on opposite sides of the center line of said draw-bar, a non-rotary slideable locking-jaw having a contour like that of the Janney type of coupling mounted and having direct movement on said seat or way, and a flange and an extension thereon moving in said ways respectively whereby the drawing strains on said locking-jaw are transmitted to said draw-head and said draw-bar.

4. A car-coupling comprising a draw-bar, a draw-head comprising a side horn on the lower portion thereof, an inclined seat or way thereon, an oppositely-disposed lower side horn, an upper guide or buffer within said horns, a lower guide or buffer connecting said horns, said horns projecting both above and below said lower guide or buffer, a non-rotary slideable locking-jaw having a contour like that of the Janney type of coupling mounted and having direct movement on said seat or way, and means carried by said jaw whereby the drawing strains are transmitted to said draw-head and said draw-bar.

5. A car-coupling comprising a draw-bar, a draw-head comprising a side horn on the lower portion thereof, an inclined seat or way thereon, an oppositely-disposed lower side horn, an upper guide or buffer within said horns, a lower guide or buffer connecting said horns, guides or ways in said draw-head rearwardly of said guides or buffers and disposed on opposite sides of the center line of said draw-bar, a non-rotary slideable locking-jaw having a contour like that of the Janney type of coupling, mounted and having direct movement on said seat or way, and having a flange and an extension thereon moving in said ways respectively whereby the drawing strains are transmitted to said draw-head and said draw-bar, and means limiting the extent of movement of said locking-jaw from impact with an opposed coupling.

6. A car-coupling comprising a draw-bar, a draw-head comprising a side horn on the lower portion thereof, an inclined seat or way thereon, an oppositely-disposed lower side horn, upper and lower guides or buffers spaced apart, said lower guide or buffer connecting said horns, a spur projecting from said upper buffer, and guides or ways in said draw-head disposed on opposite sides of the center line of said draw-bar, a non-rotary slideable locking-jaw having a contour like that of the Janney type of coupling mounted and having direct movement on said seat and below said spur, a flange and an extension thereon moving in said ways respectively whereby the drawing strains are transmitted to said draw-head and said draw-bar, and means limiting the extent of movement of said locking-jaw from impact with an opposed coupling.

7. A car-coupling comprising a draw-bar, a draw-head comprising a side horn on the lower portion thereof, an inclined seat or way thereon, an oppositely-disposed lower side horn, upper and lower guides or buffers spaced apart, said lower guide or buffer connecting said horns, a spur projecting from said upper buffer, an overhung incline thereon, guides or ways in said draw-head disposed on opposite sides of the center line of said draw-bar, a non-rotary slideable locking-jaw having a contour like that of the Janney type of coupling mounted and having direct movement on said seat and below said spur, a flange and an extension thereon moving in said ways respectively whereby the drawing strains are transmitted to said draw-head and said draw-bar, and means limiting the extent of movement of said jaw from impact with an opposed coupling.

8. A car-coupling comprising a draw-bar, a draw-head comprising a side horn on the lower portion thereof, an inclined seat or way thereon, an oppositely-disposed lower side horn, an upper guide or buffer within said horns, a lower guide or buffer connecting said horns, said horns projecting both above and below said lower guide or buffer, opposed stops carried by said side horn, and on the bottom of said guide or buffer respectively, a non-rotary slideable locking-jaw having a contour like that of the Janney type of coupling mounted and having direct movement on said seat or way, and means carried by said jaw whereby the drawing strains are transmitted to said draw-head and said draw-bar.

9. A car-coupling comprising a draw-bar, a draw-head, comprising a side horn on the lower portion thereof, an inclined seat or way thereon, an oppositely-disposed lower side horn, an upper guide or buffer within said horns, a lower guide or buffer connecting said horns, said lower guide or buffer having a bulged portion adapted to engage said first-mentioned side horn, a non-rotary slideable locking-jaw having a contour like that of the Janney type of coupling mounted and having direct movement on said seat or way, and means carried by said jaw whereby the drawing strains are transmitted to said draw-head and said draw-bar.

10. A car-coupling comprising a draw-bar, a draw-head comprising a side horn on the lower portion thereof, a ledge or seat thereon, an inclined seat or way thereon, an oppositely-disposed lower side horn, an upper guide or buffer within said horns, a lower guide or buffer connecting said horns, guides or ways in said draw-head rearwardly of said guides or buffers and disposed on opposite sides of the center line of said draw-bar, a non-rotary slideable locking-jaw having a contour like that of the Janney type of coupling mounted and having direct movement on said seat or way and said rest or ledge, and having a

flange and an extension thereon moving in said ways respectively whereby the drawing strains thereon are transmitted to said draw-head and said draw-bar, and means limiting the extent of movement of said locking-jaw 5 from impact with an opposed coupling.

11. A car-coupling comprising a draw-bar, a draw-head comprising a side horn on the lower portion thereof, a ledge or seat thereon, 10 an inclined seat or way thereon, an oppositely-disposed lower side horn, an upper guide or buffer within said horns, a lower guide or buffer connecting said horns, guides or ways in said draw-head rearwardly of said guides 15 or buffers and disposed on opposite sides of the center line of said draw-bar, a non-rotary slidable locking-jaw having a contour like that of the Janney type of coupling mounted

and having direct movement on said rest or ledge and said seat or way and having a 20 flange and an extension thereon moving in said ways respectively whereby the drawing strains thereon are transmitted to said draw-head and said draw-bar, means limiting the extent of movement of said locking-jaw from 25 impact with an opposed coupling, and a rabbit and fillet on said inclined seat and said slidable locking-jaw respectively.

In witness whereof I have hereunto affixed my signature, this 6th day of December, 1904, 30 in the presence of two witnesses.

JOHN E. WADE.
